WITNESS

M. Bell

INVENTOR,

Ernest Barber,
John M. Bell
ATTORNEY.

UNITED STATES PATENT OFFICE.

ERNEST BARBER, OF PATERSON, NEW JERSEY.

LET-OFF MECHANISM FOR LOOMS.

Application filed November 22, 1922. Serial No. 602,640.

To all whom it may concern:

Be it known that I, ERNEST BARBER, a citizen of the United States, residing at Paterson, in the county of Passaic and State 5 of New Jersey, have invented certain new and useful Improvements in Let-Off Mechanisms for Looms, of which the following is a specification.

This invention relates to mechanism for 10 frictionally controlling the rotation of the beam (as the let-off beam in a loom) from which a warp or other sheet is delivered by draft exerted on the sheet. In looms it is common to use a rope or equivalent flexible 15 device wrapped one or more times around the beam and having the end which extends relatively reversely to the free end of the warp provided with a normally pendent weight and the other end either attached 20 to some fixed point or provided with a weight which as the beam is rotated by the pull of the warp contacts with the floor or other stop, thus to relax the rope and permit the beam to rotate relatively to it. It 25 is known that such means is unsuitable for certain purposes, as in the weaving of fine fabrics where it results in imperfections being produced in the weave, such as so-called "shyers", which are an irregular 30 spacing of the filling or weft threads due to the letting-off action not being uniform in character, this in turn being due to the advances of the beam relatively to the rope or equivalent being jerky or sudden rather 35 than gradual in character. The object of this invention is to provide a let-off mechanism in which the movement of the beam under the pull of the warp or other sheet shall be at all times gradual and smooth, all 40 tendency of the beam to stick to the braking medium (which is primarily responsible for jerkiness in the action) being eliminated.

In the drawings,

Fig. 1 is a side elevation of the improved 45 let-off mechanism;

Fig. 2 is a rear elevation;

Fig. 3 is a fragmentary side elevation on a larger scale, partly in section; and

Fig. 4 is a fragmentary section on line 50 4-4, Fig. 3.

A suitable support is afforded by the stand *a*, which may be a part of a loom frame *b*. In the support is journaled the beam *c* having a head *c'* grooved peripher-

ally as at *c''*. The warp delivered from the beam is indicated at *d*.

The means to exert constricting pressure on the beam in the present example includes a rope *e* which is formed with wrappings *e'* extending around the beam head *c'* and has the forward end thereof connected with the floor by the spring *f* and the other end weighted, as by being connected to a suitably fulcrumed lever *g* which carries 60 weighting means *h*. It also includes in the present example a series of bolsters *i* which and the manner of connecting them together will be later described in detail and which serve in such example to support the wrappings of the rope and afford bearings for the rolling pressure-transmitting intermediaries.

The rolling pressure-transmitting intermediaries are in the present example rollers 75 *j*. In such example these roll on the surface of the groove *c''* of the beam-head and have bearings in the bolsters.

Each bolster includes a block which straddles the periphery of the beam-head *c'* and has inwardly projecting bearing lugs *i'* in which is suitably held, as by cotter-pins *h'* as shown, a spindle *k* on which the rollers *j* are journaled; the block also has outwardly projecting lugs *i''* which together form a 80 recessed seat in the bolster adapted to receive the wrappings of the rope *e*, as shown. Each bolster with the rollers journaled therein is connected with two other such bolsters (one on each side thereof), so as to form an 85 endless flexible system, by links *l*. In the example illustrated it is indicated that the blocks may at intervals be omitted, if desired, there being no blocks shown assembled with the alternate spindles *k*.

When the improved mechanism is in use the warp is delivered in a manner devoid of all jerkiness or sudden slippage, and this is so whether by adjustment (as by increasing or decreasing the weight *h*) the tension 100 and consequently the resistance opposed to the rotation of the beam is made great or little. Moreover, this delivery takes place without jerkiness, but in a gradual or eased manner, although each opening of the shed involves a rotary advance and each closing of the shed a rotary compensating recession of the let-off means, so that said means is constantly oscillating. Again, since adhesion as between the beam and the constrict-

ing means is practically eliminated the strain on the material being delivered is greatly reduced and its elasticity is preserved.

5 Having thus fully described my invention, what I claim as new and desire to secure by Letters Patent is:

In combination, a supporting structure, a beam journaled therein and adapted to have 19 the material to be delivered wound thereon,

means to exert constricting pressure on the beam held against rotation therewith and including a flexibly connected system of bolsters embracing the beam, and rolling pressure-transmitting intermediaries interposed relatively between the bolsters and the beam. 15

In testimony whereof I affix my signature.

ERNEST BARBER.
